UNITED STATES PATENT OFFICE

EDWARD SKILLMAN AND GUY HARMON, OF BARTLESVILLE, OKLAHOMA, ASSIGNORS TO
DOHERTY RESEARCH COMPANY, OF NEW YORK, N. Y., A CORPORATION OF DELA-
WARE

AUTOMATIC SYSTEM FOR BURNING FUEL UNDER BOILERS

Application filed October 13, 1924. Serial No. 743,367.

The present invention relates to automatic systems for burning fuel under boilers.

It has been proposed to burn either liquid or gaseous fuels under boilers and to regulate the intensity of the fire inversely as the steam pressure, or roughly so, so that the process of raising the steam should require a minimum of attention. Systems of the type just referred to have been installed to some extent, but their expense has limited their application. Moreover, such systems have required more attention than desirable. No system has been introduced heretofore which has met the practical requirements as to burning liquid fuel automatically well enough to be installed in individual boilers and particularly in the installations operating under severe conditions such as obtain in the oil fields or other places where boilers are moved from place to place at relatively short intervals.

It is one of the objects of the present invention to provide a simple and reliable automatic fuel firing system and one sufficiently cheap and compact to permit its wide use.

A second object of the present invention is to provide a reliable automatic oil burning equipment capable of being readily moved from place to place and set up in new locations.

The novel features of the present invention are pointed out with particularity in the appended claims. The invention itself, together with other objects and advantages, will best be understood from the following description taken in connection with the accompanying drawings, in which:

Fig. 1 is an elevation partly in section, of a locomotive type boiler equipped with an automatic oil burning system according to the present invention;

Fig. 2 is an elevation on a larger scale and looking in the same direction as Fig. 1 of the burner and draft controlling motor and associated parts according to the present invention. In Fig. 2 the draft and fuel controlling motor is shown in section for purposes of illustration.

Fig. 3 is an elevation of the apparatus illus-

trated in Fig. 2 when looking in the direction indicated as 3—3 in Fig. 2.

Fig. 4 is a section of the fuel and steam controlling valve according to the present invention taken on line 4—4 of Fig. 5, the valve being shown in position giving minimum burner flame.

Fig. 5 is a section of the fuel and steam valve taken on the line 5—5 of Fig. 4.

Fig. 6 is a view similar to Fig. 4, but showing the fuel valve in position for maximum burner flame; Fig. 7 is an end view of the plug of the fuel and steam valve.

In the drawing 10 indicates a boiler having a fire box 12, boiler 10 being equipped with a fuel firing and steam regulating system according to the present invention. Boiler 10 has also a steam dome 14 from which steam for use is led off through steam line 16. Connected to the steam line 16 is a boiler regulator 18 having a vacuum line 20 connected thereto. Regulator 18 is of a known type adapted to create a vacuum or subatmospheric pressure on line 20 which is of greater intensity, or in other words of less absolute pressure, as the steam boiler pressure increases. The construction of the regulator 18 forms no part of the present invention, and is not claimed herein, but is preferably of the construction disclosed in the prior application of James P. Fisher, Serial No. 723,842, filed July 2, 1924, for boiler governor.

The fire box 12 is illustrated as being set over an auxiliary combustion chamber or furnace 22 which may be of suitable brick or fire clay construction to withstand the oil flame. One wall of the furnace 22 is illustrated as having an aperture 24 therein looking toward the smoke box end of boiler 10. Inserted into the aperture 24 is a box 26 acting as a combined burner support and air inlet flue. An oil burner 28 is mounted within the box 26 adjacent the end of box 26 projecting into the wall of furnace 22. Burner 28 is illustrated as affixed to a steam pipe 32 and an oil pipe 30. Pipes 30 and 32 are run parallel to one of the vertical side walls of the box 26 on the outside of the box, passing through a door 27 forming part of the side 100

wall near its longitudinal center and thence running within the box to the burner 28. Near the end of the box 26 removed from the furnace 22 is mounted a combined steam and oil valve mechanism 34. A flange 38 formed on the mechanism 34 is affixed to side of box 26 so as to cover an aperture in the side of the box. Rotatably mounted within the body of the mechanism 34 is a valve plug 40 having suitable valve ways therein for permitting the flow of both the oil and steam and for regulating such flow. The valve ways through plug 40 are of similar shape, the way for the steam being illustrated at 42 in Figs. 4 and 6 and the way for oil being illustrated at 43 in Fig. 5. The mechanism 34 comprises two bosses 46 and 48 for the oil and steam respectively. The pipes 30 and 32 for the oil and steam are each interrupted at 26 the valve casing 34 and connected to the bosses 46 and 48. Oil pipe 30 is connected to a source of oil under pressure, preferably at nearly constant pressure, and pipe 32 is connected to steam dome 14; valves 31 and 33 being provided in the two lines.

According to the present invention, means are provided whereby the valve 40 is automatically thrown from the position giving the maximum flow of oil and steam and consequently the maximum flame to that giving minimum flow of oil and steam and consequently the minimum flame. It is desired, however, according to the present invention that the flame not be entirely extinguished at 35 any time and for this reason the opening 42 is made in the form illustrated and in which there is a small opening 44 permitting passage of fluid even when the plug 40 has been turned to its position of minimum flow.

10 The air for maintaining the flame in furnace 22 is introduced through the box 26 on which burner 28 is mounted. The valve plug 40 projects through the wall of box 26 as illustrated in Figs. 3 and 5, and the end of the 15 plug 40 within the box 26 is slotted as illustrated at 50 (Figs. 5 and 7) to receive the edge of a damper 52. Damper 52 is mounted to swing on a horizontal axis within the box 26, one edge of the damper being fixed in the 20 slot 50 so that the plug 40 serves as one pivot for damper 52, the other pivot being illustrated as projecting through the wall of box 26 at 54, opposite the plug 40.

The air for maintaining the flame in the 55 boiler furnace is introduced through the box 26 in which the burner 28 is mounted. The amount of air used for combustion is carefully regulated so as to supply the air in accordance with the volume of oil to be burned.

60 The control of air is maintained by means of the damper 52 which is mounted within the box 26.

Valve plug 40 and damper 52 are operated simultaneously and automatically according 65 to the present invention by means of a motor

56 mounted on top of box 26 and operated by the vacuum pressure developed by the boiler regulator 18. As is clearly illustrated in Figs. 2 and 3, the motor 56 comprises a closed casing split along the central horizontal line at 58 to receive a diaphragm 60 which is clamped between the two portions of the motor casing. Fixed to diaphragm 60 within the casing of the motor 56 are weights 62. The diaphragm 60 is adapted to move up and down carrying with it the weights 62, depending upon the differences in pressure on its opposite sides. The vacuum line 20 of the boiler regulator is connected into the casing of motor 56 above the diaphragm 60, the lower face of the diaphragm being exposed to atmospheric pressure admitted into the casing of the motor through aperture 64 illustrated as being in the center of the bottom of the casing. A piston rod 66 is connected to diaphragm 60 and weights 62 as illustrated and extends through the aperture 64 and thence downwardly through the top of the box 26, the lower end of the rod 66 being pivotally connected to a bracket 68 fixed to one face of the damper 52 (Figs. 2 and 3). Damper 52 is slotted as illustrated at 70 (Fig. 3) so that the damper may swing on its axis without interference from the rod 66. Also, a set screw 72 is threaded into the top of the casing of motor 56 and can be adjusted to contact with the upper weight 62 so as to hold the valve plug 40 and the damper 52 in the position for minimum flame. The weights 62 are positioned on the rod 66 so that the lower of the weights 62 shall rest on the bottom of the casing of motor 56 when the damper 52 and valve plug 40 are in the position for maximum flame.

It will be seen from the foregoing that as the diaphragm 60 is moved up and down by changes in pressure on its opposite faces, the rod 66 will turn the damper 52 and the valve plug 40. The parts are so arranged that when the diaphragm 60 is in its uppermost position, the damper 52 cuts down the flow of air through box 26 to a minimum, and at the same time the plug 40 cuts down the flow of oil and steam also to a minimum. When the diaphragm 60 and weights 62 are in their lowermost position, the damper 52 is substantially horizontal to permit the maximum flow of air through box 26 and the flow of oil and steam is such as to produce a maximum flame. This maximum flame for any given boiler and furnace conditions is adjusted in the ordinary manner by adjusting the oil valve 31 and steam valve 33 permitting the greatest oil flow possible under the given boiler conditions without causing incomplete combustion.

The diaphragm 60 and weights 62 are subject only to the action of gravity and to the pressures as previously described. Consequently if the difference in the pressure on

the two sides of diagram 60 is sufficient to lift the weights 62 they will move upwardly without intermission until the parts produce the minimum flame conditions as before described. As soon now as the pressure conditions of diaphragm 60 are insufficient to support the weights 62, the weights will move down without intermission and the parts will assume the position giving maximum flame 5 as above described. This action will be slightly retarded, to be sure, by the effects of friction in the valve mechanism 34 and on the pivot 54, but when the weights once begin to move they will travel uninterruptedly from the maximum position to the minimum or the reverse without interruption.

As before mentioned, governor 18 produces a maximum vacuum on the line 20, and consequently in the upper part of the motor 56 20 under conditions of maximum steam pressure. Therefore in the operation of the apparatus, the parts being assumed as giving the maximum flame, as soon as the demand for steam permits, the steam pressure will 25 rise to a predetermined maximum at which point the motor 56 will shift the valve and damper to give a minimum flame. When now the use of steam or the effect of heat losses has reduced the steam pressure to a 30 predetermined minimum, the motor 56 will throw in a maximum flame again.

It will be observed that no attempt is made to graduate the intensity of the flame in accordance with the demand for steam or in accordance with the steam pressure except as 35 determined by the desired maximum and minimum flame conditions. Such graduated regulation, although often attempted in the past, introduces unnecessary complications in the apparatus, and at least as good fuel economy can be obtained without such features. As the conditions of the maximum and minimum flames are the only ones under 40 which the apparatus operates for any appreciable time, it is unnecessary to adjust closely the relation between air, steam and the oil flow for any other conditions, but the passages in the plug 40 are so proportioned and valves 31 and 33 in the oil and steam lines 45 respectively so adjusted and the damper opening so regulated that the fuel is burned to best advantage both at maximum flame and minimum flame.

Having thus described our invention, we 55 claim:

1. The combination of a portable conduit adapted to supply air for combustion to the fire-box of a furnace, a casing containing a weighted motor element, a damper for controlling air flow through said conduit, a fuel valve, a steam valve, said fuel and steam valves having movable elements mounted on the axis of said damper and connected to turn therewith, operating connections between 60 said motor element and said axis, a fuel

burner, and fuel and steam pipes connecting said valves and said burner.

2. The combination of a conduit adapted to supply air for combustion to the fire-box of a furnace, a motor element, a damper for controlling the flow of air through said conduit, a fuel valve, a steam valve, each of said valves having a passageway at right angles to that of the other and having its movable element mounted on the same axis as said damper and connected to turn therewith, operating connections between said motor element and said axis, a fuel burner, and fuel and steam pipes connecting said valves and said burner. 70

3. The combination of a conduit adapted to supply air for combustion to the fire-box of a furnace, a motor element, a damper pivoted on a rotatable axis, a lug fixed to one side of said damper near said axis, a rigid connection between said motor element and said lug, said damper being slotted to accommodate said rigid connection, a fuel valve, an atomizing fluid control valve, said valves having their movable elements mounted on the same axis as said damper and connected to turn therewith, a fuel burner, and fuel and atomizing fluid supply pipes connecting said valves and said burner. 80

4. The combination of a conduit adapted to supply air for combustion to the firebox of a furnace, a casing having a weighted motor element therein, a damper pivoted on a rotatable axis for controlling air supply through said conduit, a projection fixed to one side of said damper near said axis, and a connection between said motor element and said projection. 95

5. The combination as set forth in claim 4 together with a fuel valve fixed to the exterior of the conduit, a steam valve fixed to the exterior of said conduit, said valves having their movable elements mounted on the same axis as said damper and connected to turn therewith, a fuel burner, and fuel and steam pipes connecting said valves and said burner. 105

6. The combination of a portable conduit adapted to supply air for combustion to the firebox of a furnace, a casing containing a weighted motor element and fixed to said conduit, a damper within said conduit, a fuel valve fixed to the exterior of said conduit, a steam valve fixed to the exterior of said conduit, each of said valves having a passageway at right angles to that of the other and the valves having their movable elements connected and mounted to turn on the same axis, operating connections between said motor elements, said damper and the movable elements of said valves, a fuel burner, and fuel and steam pipes connecting said valves and said burner. 115

7. The combination of a portable conduit adapted to supply air for combustion to the 120

firebox of a furnace, a damper mounted on a horizontal axis and within said conduit, an offset fixed to said damper near said axis, a casing mounted on top of said conduit and containing a weighted flexible diaphragm and a connection between said diaphragm and said offset, said casing and conduit being apertured to receive said connection.

In testimony whereof, we affix our signatures.

EDWARD SKILLMAN.
GUY HARMON.
